MARINE AIR CONDITIONER

Paul Bunten, 1221 Barrow Dale Road,
Rydal, Pa. 19136

Filed Apr. 12, 1973, Ser. No. 350,440

Term of patent 14 years

Int. Cl. D23—04

U.S. Cl. D23—142

FIG. 1

FIG. 2

FIG. 4

FIG. 3

FIG. 5

FIG. 6

FIG. 7

FIG. 1 is a front perspective view of a marine air conditioner showing my new design;

FIG. 2 is a right side elevation view thereof;

FIG. 3 is a rear view thereof;

FIG. 4 is a top plan view thereof;

FIG. 5 is a bottom view thereof;

FIGS. 6 and 7 are enlarged cross-sectional views taken on lines 6—6 and 7—7, respectively, of FIG. 1.

The undisclosed left side is a mirror image of the right side elevation view of FIG. 2.

I claim:

The ornamental design for a marine air conditioner, substantially as shown and described.
